UNITED STATES PATENT OFFICE.

ARSENE HEBERT, OF MANCHESTER, NEW HAMPSHIRE, ASSIGNOR TO
HERBERT B. NEWTON, OF HAVERHILL, MASSACHUSETTS.

HAND TACKING-TOOL.

SPECIFICATION forming part of Letters Patent No. 695,554, dated March 18, 1902.

Application filed May 16, 1901. Serial No. 60,464. (No model.)

To all whom it may concern:

Be it known that I, ARSENE HEBERT, a subject of the King of Great Britain, residing at Manchester, in the county of Hillsboro and 5 State of New Hampshire, have invented certain new and useful Improvements in Hand Tacking-Tools, of which the following is a specification.

This invention relates to certain improvements in hand tacking-tools or pincers which are especially designed to be employed in lasting shoes.

Prior to this invention I have produced various forms of hand tacking-tools, three of 15 which are described in my prior patents, Nos. 620,650, 670,491, and 670,403. These tools are open to several serious objections which it is the object of this invention to overcome.

One of the chief objections to the prior devices referred to is the great liability of the 20 tack being thrown or jerked back by the act of striking down with the hammer, so that it will be thrown out of position to be engaged by the driving-plunger after it has been 25 dropped into the feed-passage of the hammer. If this occurs, not only will the hammer miss driving a tack when it should, but a second tack will be dropped into the tube, causing the hammer to become clogged in 30 many cases. Another objection resides in the fact that in these prior devices the tack must drop nearly the entire length of the hammer before it reaches a stopping-place, so that if a second blow is struck very quickly sufficient 35 time will not have elapsed to permit the tack to reach a position in which it will be engaged by the plunger when the next blow is struck.

In the prior devices referred to the mechanism for feeding the tacks one by one into the hammer from the raceway is also more or less defective, and with all prior devices, so far as I am aware, it has been impossible to drive two tacks close together without driving one of them into the head. It has also been found extremely difficult with these prior devices for the workman to drive the tack sufficiently straight and with sufficient force to cause it to enter a hard leather or 45 leather-board sole, principally because the

hammer slides on the outside of the feed-tube, and therefore a short guiding-surface is provided for it, so that if the workman should strike on the edge of the hammer in a direction other than directly in line with its sliding movement or other than flat upon its face the hammer will bind on the tube, so that it will not be forced back sufficiently to drive in the tack and will swing out of line, so that the tack will not be driven straight and will often 60 be bent.

The objects of my invention are to produce a tool of the above-named character in which all possibility of the tack being thrown up or out of position in the act of striking will be 65 avoided, in which the tack will be seized while in the tack-raceway and positively conducted to the point where it will be engaged by the tack-driver, which will hold the tack so that it may be driven straight into either 70 hard or soft leather, in which two tacks may be partially driven close together, and in which the work may be struck by the hammer in almost any direction without causing the reciprocating part to bind to any appreciable 75 extent, and thereby interfere with the driving of the tacks.

I accomplish the above-named objects of my invention by employing a tool in which the outer or hammer part and the driving-pin or 80 driver are both fixed to the handle or main part of the pincers, and the tube through which the tacks pass is slidably connected to the hammer inside thereof, so that a long bearing-surface is provided therefor, thus avoiding all liability of binding in whatever direction the blow is struck. I further provide 85 the feed-tube with a notched latch which is moved so that the tack may pass below the notch when it leaves the feeder and will be 90 firmly clamped against the side of the feed-tube by the latch the instant the notch in the latter passes beyond the end of the driver, so that all possibility of the tack being jerked back out of place is avoided. I further arrange a portion of the driver and feed-tube outside of the face of the hammer, so that a 95 tack may be driven close to another tack which has previously been driven without striking the latter. These and other features 100

of my invention will be better understood by reference to the accompanying drawings, in which—

Figure 1 is a central cross-section taken on the line X X of Fig. 4, the parts being shown with the sliding part in its outermost position. Fig. 2 is a similar view of the principal parts of the device with the sliding part in its innermost position. Fig. 3 is a cross-section on the line Y Y of Fig. 2. Fig. 4 is a partial plan view of the device with the parts in the position shown in Fig. 1, the cover to the feed-channel being removed. Fig. 5 is a similar view to Fig. 4 with the parts in the position shown in Fig. 2. Fig. 6 is a detail view of the under side of the raceway-cover. Fig. 7 is a view of the face of the hammer. Figs. 8 and 9 are detail views of the upper latch and driver, respectively. Fig. 10 is a side elevation of the tool complete. Figs. 11 and 12 are enlarged cross-sections of the feeder and its closely-associated parts, the positions being the same as in Figs. 1 and 2, respectively. Fig. 13 is a similar view on the line z z of Fig. 11.

In the drawings the same numerals indicate the same parts throughout.

The main body or stationary member 1 of the pincers is provided with a handle 2 and jaw 3, which are formed integrally therewith, and a hammer 4, which is firmly connected thereto by pins or screws. A second handle 5 and jaw 6 are pivoted to the main body 1 and connected by the link 7 in the usual way. The tack-magazine 8 is secured to the front part of the main body 1, and said magazine is provided with oppositely-arranged diverging plates 9, which are secured to or formed integrally with the vertical plates 11, which are arranged closely adjacent each other and constitute the tack-raceway. These plates 11 extend rearwardly, and their upper edges are inclined downwardly to a vertical shoulder 110, beyond which the edges are horizontal. The ends of said plates 11 are inclined at 111, as indicated in Figs. 1 and 2. The tack driver or plunger 12 is secured to the main body 1 by means of a lateral projection 120 or any other convenient means, and said driver extends downwardly and terminates slightly below the face of the hammer 4. The front side of the driver is provided with two notches 13 and 14 and a projecting lip 15 near its upper end. The face of the driver is made concave at its upper portion, as indicated in Fig. 9. The sliding block or feed-tube 16 is fitted in a passage which extends from top to bottom of the hammer 4 and body 1, said block being provided with two laterally-projecting lugs 17 and 18 on each side thereof and two guiding-flanges 19 and 20, said lugs being fitted in corresponding grooves in the hammer 4 and said guiding-flanges being fitted in guideways or grooves in both the main body 1 and hammer 4. Springs 170 and 180 are arranged between the under side of body 1 and the upper sides of said lugs and act constantly to press said block outwardly. The block 16 is preferably

made rectangular in form and projects laterally beyond the rear side of the hammer 4. The driver 12 is preferably made square or rectangular in cross-section and is arranged in a rectangular passage 10, which extends from top to bottom of the block 16, with its front side approximately in line with the rear side of the periphery of the hammer, as shown in Fig. 7. A series of latches 21, 22, and 23 are pivoted in the passage 10, said latches being constantly pressed toward the face of the driver by springs 24, 25, and 26, respectively, said springs being located in chambers in block 16, the ends of which opposite the latches are closed by screw-plugs. The upper and lower latches 21 and 23 are preferably provided with notches 27 and 28, and said latch 21 is also provided with a projecting flange 210, as indicated in Figs. 1, 2, and 8, said flange being arranged on the right-hand side thereof and in the same plane as the flange 15 on the driver. The pivot-pins of said latches preferably pass through elongated apertures in each instance, so that each latch is susceptible of both swinging and lateral movements. The latch 21 is preferably provided with two pivots instead of one, and its upper end is reduced in thickness, so that it may pass between the plates 11 for reasons hereinafter explained. (See Figs. 3 and 8.) The tack-feeder 29 is pivoted at 30 on the upper side of the main body 1, said feeder being made in the form of a flat plate and being provided with a rearwardly-projecting lug 31 and two arms 32 and 33, which extend forwardly and are then bent toward each other and inclose a space which is directly above two upwardly-extending fingers 34 and 35, which are formed on the upper end of the sliding block 16 on each side of passage 10 and driver 12, said finger 34 having an inclined side 340. (See Fig. 3.) The arm 32 of the feeder is provided with two prongs 36 and 37, the prong 36 being slightly recessed on the side next the prong 37, so that a diagonally-extending notch 360 is formed between them. The opposite arm 33 is provided with a V-shaped prong 38 at its end, the point of which is opposite the notch 360 and slightly in front of the inner end thereof, all as shown in Figs. 4 and 5. The arms 32 and 33 of the feeder are arranged to swing as closely as possible to the shoulder 110 on the plates 11. A spring 39 (see Fig. 1 and dotted lines Figs. 4 and 5) bears against said lug 31 and acts to constantly throw the feeder 29 to the position shown in Fig. 4. A raceway-cover 40 is arranged over the raceway formed between the plates 11 and extends into the tack-magazine a short distance from the tack-collector plates 9. The opposite end of said cover 40 is provided with a lug 42, by which the cover may be removably secured to the main body 1 by a pin 43 or any other suitable means. The upper side of the cover is provided with a groove 41, which extends from the inner end thereof to the face of the driver 12, the depth

and width of said groove being sufficient to permit the free passage of the head of a tack of any size which will be likely to be used. The inner or front end of the groove 41 is provided with a projecting lip 44, said lip being slightly in front of a notch 45, which is formed in the edge of each plate 11. Two projecting plates 46 are secured in a recess in the under side of the cover 40 directly over the ends of the arms 32 and 33 of the feeder-plate, the ends of said plates 46 being so arranged with respect to each other that they will permit the passage of the body of the tacks therebetween, but will not permit the passage of the heads thereof. (See Figs. 6 and 13.) The front sides of said plates 46 are arranged in notch 47 in the edge of the raceway-plates 11 just above the shoulder 110 and at the end of the inclined portions thereof, (see Fig. 11,) so that when a tack slides down the raceway the head thereof will pass onto the plates 46 and its body will be suspended by and between them. The groove 41 is open beyond the plates to its end, so that the tacks may drop directly into passage 10 as soon as they pass said plates.

The rear edge of the block 16 is provided with two notches 48 and 49, and a spring-pressed lever 50 is pivoted to the body 1, so that the tooth 51, formed thereon, may engage said notches 48 and 49 when the block is pushed inwardly and hold it either in an intermediate position or so that its face will be flush with the face of the hammer.

Having described the general construction of my device, the operation thereof may be described as follows: The tack-magazine is filled with tacks in the usual way, and as it is shaken up and down the tacks will be collected by the plates 9 and conducted down the raceway to the end of the incline thereof, where they are stopped by the prong 37 on the feeder-plate 29. The notch 45 and projection or lip 44 prevent the tacks from being thrown out of the raceway when the workman strikes down with the tool. When the work is struck by the block 16, the latter will be forced into the hammer and the inclined side 340 on the upwardly-extending finger 34 at the top of said block will engage the inner side of the arm 32 of the feeder. When the block 16 has been forced nearly into its limit, it will cause the feeder to swing to the right, and when the block 16 is forced in fully to the position shown in Fig. 2 the prong 37 will have passed to one side of the raceway, as shown in Fig. 5, permitting the tack to pass the end of said prong. The lateral movement of the feeder 29 carries the prong 38 across the raceway, so that it will engage the tack which has passed the end of prong 37, thus permitting only one tack to pass the prong 37. When the block 16 is again forced outwardly by the springs 170 and 180, the spring 39 will swing the feeder 29 back to the position shown in Fig. 4 as soon as the block is lowered sufficiently to move the finger 34 out of

engagement with arm 32. As the incline which is formed on the projection 34 is very abrupt, the distance which the block will need to move before the feeder will be swung back is very slight. The tack which has passed the point of prong 37 will be carried into the end of the notch 360 beyond the end of prong 38 as the feeder swings back to the position shown in Fig. 4. When the block 16 is again forced inwardly, swinging the feeder 29 as before, the tack, which has its body portion located in the notch 360 and which is also supported by its head on the projecting plates 46, (see Figs. 11 to 13,) will now be engaged by the rear face of the prong 38 and carried rearwardly, so that it drops into the passage 10 between the ends of the raceway and the face of the driver 12. In the meantime another tack has passed the prong 37 and into the notch 360 beyond it. As the block 16 is forced upwardly the lips 15 on the driver and 210 on the upper latch 21 come into engagement, so that the pointed upper end of said latch will be swung away from the driver, said pointed upper end passing between the tack which is in the notch 360 at the end of arm 32 and the tack which is resting against the prong 37 in the raceway, as shown in Fig. 2. This action causes the notch 27 on the latch 21 to be moved so that when the tack is dropped into the passage between it and the driver it will readily pass below said notch 27 and lodge between the latch and the driver, as shown in Fig. 2. The pointed upper end of the latch 21 separates the two tacks which were in engagement with the feeder and prevents any lateral tipping thereof which might possibly interfere with the proper feeding of the tack into the tack-passage 10 of the block 16. As the tack is dropped into the tack-passage 10 between the latch 21 and the driver 12 the block 16 is again forced out to its limit, so that the upper notch 13 on the driver passes above the notch 27 on the latch, the latter notch preventing the tack from being drawn up beyond the latch 21 by the driver as the latch is carried down with the block 16. The length of lip 15 is sufficient to hold latch 21 away from the driver until the block is nearly forced out to its limit, giving the tack ample time to drop into place. Then the latch is permitted to grasp the tack just as the block reaches its outermost position. When the block is again forced inwardly, the notch 13 engages the head of the tack and forces it down below the end of the latch 21, as shown in Fig. 2. The lower end of the latch 21 is preferably made square, and the latch 22, which is directly below it, is provided with a grooved face, so that the bottom of the latch 21 will act as a notch; but obviously the result would be the same if the latch 22 were provided with a notch and the latch 21 made slightly shorter and 22 made correspondingly longer. When the block 16 is forced outwardly again, the lower driver-notch 14 passes above the bottom

of latch 21, so that the tack which is below said latch 21 will be engaged by said notch 14 when the block is again forced inwardly and the tack will be carried below the notch 28 on 5 the lower latch 23, as shown in Fig. 2. When the block is again forced outwardly, the tack, which has been forced past the notch 28, will drop down to the position shown in Fig. 1, so that it is held between the face of the latch 23 10 and the side of the passage through the block 16, directly in the path of the end of the driver 12. It will be observed that the tack which is thus held will be confined in a comparatively small space, and that it will be impossible for it to be thrown back out of the path 15 of the driver when the workman strikes down with the tool, and also that the face of latch 23 may be so shaped that the tack will be held straight in line with the driver. The result 20 is that on the next inward movement of the block 16 the end of the driver will strike this tack and force it into the work. The feeder will have in the meantime acted to supply a single tack on each reciprocation of the block 25 16, so that a series of tacks will be carried to the several positions previously described, and a single tack will be forced in position to be driven into the work whenever the block 16 is forced inwardly by striking it against 30 the work.

The functions of the lever 50 and notches 48 and 49 are the same as those described in reference to the spring-pressed trigger shown in my prior patents above referred to and 35 need not be here described.

As block 16 projects from the face of the hammer, as shown in Fig. 7, and as the driver is located outside of the general outline of the hammer, so that each tack will be driven at 40 one side of the latter, it will be apparent that a tack may be driven in partially and then a second tack driven close to it without striking the first tack and driving it home. This is a very important feature of my invention, 45 as it is necessary to have the lasting-tacks driven so that they may be readily removed, particularly in "turns" and "Goodyear welts," and it is also necessary to drive the tacks close together in many places in order 50 to last the shoe perfectly.

As the block 16 is guided throughout its entire length, affording a very long bearing-surface therefor even when it is in its outermost position, there is practically no liability 55 of its binding in the hammer when the work is struck in a diagonal direction to the path of the block. Moreover, as the lower outer corner of the block is made rounding, as shown in Figs. 1 and 2, almost any blow which 60 would otherwise be likely to cause it to bind in the hammer will not have that effect.

The feature of providing means for supporting the head of the tacks while they are being separated by the feeder and dropped 65 one by one into the feed-tube passage is an important feature of my invention, for the reason that if the slotted support formed by

plates 46 were omitted tacks having comparatively small heads would drop into the space between the prongs of the feeder and clog 70 it. The principal difficulty, however, which would arise if the tacks were not supported against lateral movement above the feeder is that the feeder would engage each tack directly under its head and tip it into a diagonal position across the raceway, thus causing 75 it to bind and its head to tip, so that its edges would pass into the space between the prongs of the feeder. The result would then be that when the movement of the feeder was reversed the tack would become jammed between the feeder and raceway, clogging the 80 feeder and preventing its feeding on the tack. When the slotted support is provided, however, the tack will be held against lateral 85 movement both above and below the feeder, so that it cannot possibly tip or become misplaced. (See Fig. 13.)

With the above-described device it will be observed that the tack will be seized practically as soon as it leaves the feeder, and it is then positively held until it is driven into the work, so that it is impossible for the tool to miss driving a tack so long as the parts are in working order. The liability of any 95 of these parts becoming disarranged is very remote.

Various modifications may be made without departing from the spirit of my invention. For example, the two upper latches might 100 be omitted and the lower latch be moved away from the driver when the feed tube or block is forced into the hammer, so that the tack would drop direct from the feeder to the lower latch and be automatically locked 105 thereby when the block is forced out, or the three latches might be made in one piece, which would be provided with notches at suitable intervals throughout its length.

Having described my invention, what I 110 claim as new, and desire to secure by Letters Patent of the United States, is as follows:

1. A hand tacking-tool comprising a relatively fixed member and a spring-pressed member which is adapted to reciprocate with 115 respect thereto, one of said members being provided with a tack-passage which extends therethrough, a driver which is secured to said fixed member and is located in said tack-passage, a notched latch which is located in 120 said passage, a spring which acts normally to press said latch against said driver, means for feeding a tack into said passage and positively moving the notched portion of said latch away from said driver when said reciprocating member is forced inwardly so that 125 a tack may pass into said passage between said driver and latch and below the notch in the latter, and means for causing said latch to positively engage the tack by the time the 130 reciprocating member has moved to its outermost position and hold the same from backward movement.

2. A hand tacking-tool comprising a rela-

tively fixed member and a spring-pressed member which is adapted to reciprocate with respect thereto, one of said members being provided with a tack-passage which extends therethrough, a driver which is secured to said fixed member and is located in said passage, a latch which is located in said passage, means which acts constantly to press said latch against said driver, means for feeding a tack into said passage and for positively moving the upper end of said latch away from the driver when said reciprocating member is forced inwardly, so that a tack may pass into said passage between said driver and the upper end of said latch, and means for releasing said latch so that it may be pressed against the tack by the time the reciprocating member has reached the outer limit of its movements, thereby positively holding the tack against backward movement.

3. A hand tacking-tool comprising a relatively fixed member having a hammer secured thereto, a spring-pressed member which is adapted to reciprocate with respect thereto and is provided with a tack-passage which extends therethrough, a driver which is secured to said hammer and is arranged in said passage, a spring-pressed latch which is arranged in said passage, is pivoted to said reciprocating member, and is normally forced against said driver, and means carried by said fixed member for engaging said latch and moving the upper end thereof away from said driver as the reciprocating member is forced inwardly, means for feeding a tack into said passage as the movable member reaches the limit of its inward movement, and means for releasing said latch.

4. A hand tacking-tool comprising a relatively fixed member having a hammer secured thereto, a spring-pressed member which is adapted to reciprocate within said hammer and is provided with a tack-passage which extends therethrough, a driver which is secured to said hammer, a latch having a notch, said latch being pivoted to said reciprocating member, a spring for pressing the same against the face of said driver, means for moving the notched portion of said latch away from the driver and for feeding a tack into said passage as the reciprocating member is moved inwardly, whereby a tack may be lodged between the latch and driver below said notch, and a notch in the face of said driver which is so arranged that the notch in said latch passes beyond it when said reciprocating member moves outwardly to its limit.

5. A hand tacking-tool comprising a relatively fixed member and a spring-pressed member which is adapted to reciprocate with respect thereto, said latter member being provided with a tack-passage which extends therethrough, a latch which is pivoted to said reciprocating member and is arranged in said passage, a tack-driver which is arranged in said passage and is secured to said fixed member, a spring for pressing said latch against

the face of said driver, a projection on said driver which is adapted to engage said latch and move it away from the driver as the reciprocating member is moved inwardly, and means for feeding a tack into said passage while the latch is held in this position.

6. A hand tacking-tool comprising a relatively fixed member having a hammer secured thereto, a spring-pressed member which is adapted to reciprocate within said hammer and has the lower end portion thereof projecting laterally beyond the periphery of the hammer, said reciprocating member having a tack-passage extending therethrough, the lower or discharge end of said passage being located partially in said projecting portion, a driver which has its lower end arranged in the outermost portion of said passage, and means for feeding the tacks in position to be engaged by the end of said driver, whereby the tacks may be driven beyond the periphery of the hammer.

7. A hand tacking-tool comprising a hammer and a feed-tube, one of which is adapted to reciprocate relatively to the other, said feed-tube being located partially without the hammer, and a driver which is located in the passage of said feed-tube with its end arranged partially outside the periphery of said hammer, and means for feeding the tacks in position to be engaged by the end of said driver, whereby two tacks may be driven closely adjacent to each other without either being struck by the hammer.

8. A hand tacking-tool comprising a relatively fixed hammer and a spring-pressed block which is adapted to reciprocate within said hammer, a flat-sided projection on said block which projects beyond the periphery of said hammer and is provided with a tack-passage, a tack-driver which is located in said passage, and means for feeding the tacks in position to be engaged by said driver as said block is forced inwardly, whereby two tacks may be driven in close proximity without either being struck by the hammer.

9. A hand tacking-tool comprising a tack-magazine, a tack-raceway leading therefrom, a feed-tube and a hammer, one of which is adapted to reciprocate with respect to the other, a tack-feeder comprising a notched plate which when actuated is adapted to conduct the tacks one by one from the raceway to the feed-tube, means for actuating said plate which are controlled by the relative positions of said feed-tube and hammer, and a slotted support above said plate which is arranged to receive the tacks from the raceway and support them by their heads while said plate is in engagement therewith.

10. A hand tacking-tool comprising a hammer and a feed-tube, one of which is adapted to reciprocate with respect to the other, a tack-magazine and a raceway leading therefrom, a tack-feeder which is arranged above and closely adjacent to said raceway at its end, said feeder comprising a notched plate which

when actuated is adapted to separate and conduct the tacks one by one from the raceway to the feed-tube, means for actuating said feeder which are controlled by the relative 5 positions of said hammer and feed-tube, a slotted support which is arranged directly over said feeder and is adapted to receive the tacks as they pass down the raceway and support the same by their heads while the feeder 10 is in engagement therewith, the slot in said support being enlarged beyond the feeder so that the tacks will be allowed to drop from said support as they are discharged from the feeder.

11. A hand tacking-tool comprising a relatively fixed member having a hammer firmly secured thereto, a spring-pressed block which is arranged to slide within said hammer, a tack - passage which extends through said 20 block from end to end, a tack-driver which is secured to said fixed member and is arranged in said passage, a spring-pressed latch which is normally forced toward said driver, a tack-raceway, a feeder which is adapted to receive 25 the tacks from the raceway and discharge them into said passage, means for actuating said feeder and for causing the same to discharge a tack on each reciprocation of said block, a projection on the upper end of said 30 latch, means for moving said latch away from said driver so that said projection passes between the tack which is about to be fed into said passage and the next succeeding tack as the block reaches its inward position, said 35 means permitting said latch to move toward the driver as the block moves outwardly and after the tack has been discharged by the feeder.

12. A hand tacking-tool comprising a relatively fixed member having a hammer firmly secured thereto, a feed-tube which is arranged to slide within said hammer, a projecting lug on each side of said tube, said hammer being provided with corresponding grooves which 40 terminate above the face of the hammer, and springs arranged between a relatively fixed portion of the tool and the upper sides of each of said lugs, whereby said springs act constantly to force said tube outwardly.

13. A hand tacking-tool comprising a relatively fixed member, comprising a hammer which is fixed thereon, a block which is

adapted and arranged to slide within said hammer, a lateral projection on said block which extends beyond the periphery of the 55 face of the hammer, a tack-passage in said projection which extends through the bottom thereof, a driver in said passage which is secured to the hammer, means for feeding a tack in position to be engaged by the driver 60 as the block is forced inwardly, the face of said projection being substantially flush with the face of the hammer when in its innermost position and being provided with a rounded corner at its outer edge. 65

14. An automatic tacking device comprising a tack-magazine, a tack-raceway leading therefrom, a relatively fixed member and a movable member, one of said members being provided with a tack-passage, a tack-feeder 70 which when actuated is adapted to separate the tacks and conduct them one by one from the raceway to said passage, means for actuating said feeder, and a slotted support above 75 said feeder which is arranged to receive the tacks from the raceway and support them by their heads while the feeder is in engagement therewith.

15. A hand tacking-tool comprising a relatively fixed member and a spring-pressed 80 member which is adapted to reciprocate with respect thereto, one of said members being provided with a tack-passage which extends therethrough, a driver which is secured to said fixed member and is located in said passage, a latch which is located in said passage, means for feeding a tack into said passage and for positively moving the upper end of 85 said latch away from the driver when said reciprocating member is forced inwardly, so 90 that a tack may pass into said passage between said driver and the upper end of said latch, and means for releasing said latch and for pressing the same against the tack by the time the reciprocating member has reached 95 the outer limit of its movements, thereby positively holding the tack against backward movement.

In testimony whereof I have affixed my signature in presence of two witnesses.

ARSENE HEBERT.
